(57) **ABSTRACT**

A new *Osteospermum* plant particularly distinguished by
white flowers with blue discs and an upright growth habit,
is disclosed.

1 Drawing Sheet

1

Genus and species: *Osteospermum ecklonis* Norl.
Variety denomination: **'KLEOE18301'**.

BACKGROUND OF THE NEW PLANT

The present invention comprises a new and distinct variety of *Osteospermum*, botanically known as *Osteospermum ecklonis* Norl., and hereinafter referred to by the variety name 'KLEOE18301'. 'KLEOE18301' originated from a cross-pollination conducted in August to September 2011 in Stuttgart, Germany between the proprietary female *Osteospermum* variety 'OE-2010-0382' (unpatented), and the male *Osteospermum* variety 'Sunny', also known as 'OE-2000-Pingo' (patent status unknown).

The seeds from the cross were sown and plants were grown in a greenhouse for evaluation, where an individual plant designated 'KLEOE18301' was selected from the group of plants in May 2011 in Stuttgart. In June 2011 in Stuttgart, 'KLEOE18301' was first vegetatively propagated by vegetative terminal cuttings. 'KLEOE18301' was found to reproduce true to type in successive generations of asexual propagation via vegetative terminal cuttings.

SUMMARY

The following are the most outstanding and distinguishing characteristics of this new variety when grown under normal horticultural practices in Stuttgart, Germany.

1. White ray florets with blue discs; and
2. An upright growth habit.

DESCRIPTION OF THE PHOTOGRAPH

This new *Osteospermum* plant is illustrated by the accompanying photograph which shows the plant's overall plant habit including form, foliage, and flowers. The photograph is of a 12-week-old plant grown in a greenhouse in Stuttgart, Germany in May 2019.

2

The colors shown are as true as can be reasonably obtained by conventional photographic procedures.

DESCRIPTION OF THE NEW VARIETY

5 The following detailed descriptions set forth the distinctive characteristics of 'KLEOE18301'. The data which define these characteristics were collected in Latina, Italy on May 16, 2019 on plants that had been potted in week 45 of 10 2018. Color references are to The R.H.S. Colour Chart of The Royal Horticultural Society of London (R.H.S.), 5th edition (2007).

Classification:

Family.—Asteraceae.

Botanical.—*Osteospermum ecklonis*.

Common.—*Osteospermum*.

Designation.—'KLEOE18301'.

Parentage:

20 Female parent.—The proprietary female *Osteospermum* variety 'OE-2010-0382' (unpatented).

Male parent.—The male *Osteospermum* variety 'Sunny' (patent status unknown).

Plant:

25 Form and habit.—Herbaceous perennial but usually cultivated as an annual; not frost resistant.

Growth habit.—Upright.

Branching habit.—Normal.

Height (from top of soil, including inflorescence).—29.4 cm.

Width (including inflorescences).—27.5 cm.

Propagation type.—Stem cuttings; vegetative terminal tip cuttings.

Time to produce a finished flowering plant.—9 weeks.

Time to initiate and develop roots.—4 weeks.

Root description.—Fine and white, RHS 155A.

Stems:

Total number of branches per plant (calculated at the base of the plant).—6.

Length.—27.0 cm.	5	Peduncle:
Diameter.—0.9 cm.		Length.—10.1 cm.
Internode length.—3.9 cm.		Diameter.—0.2 cm.
Color.—RHS 143B.	5	Texture.—Smooth with hairs.
Texture.—Smooth.		Color.—RHS 143C.
Anthocyanin.—Absent.		Phyllaries:
Leaves:		Arrangement.—Single.
Arrangement.—Alternate.		Observed quantity per flower.—15.
Shape.—Obovate.	10	Shape.—Lanceolate.
Apex.—Obtuse.		Apex.—Acute.
Base.—Acute.		Base.—Obtuse.
Margin.—Entire.		Margin.—Entire.
Immature color.—Upper surface: RHS 143A. Lower surface: RHS 143B.	15	Length.—0.9 cm.
Mature color.—Upper surface: RHS N137A. Lower surface: RHS 138A. Length: 7.1 cm. Width: 4.1 cm.		Width.—0.2 cm.
Texture.—Upper surface: Leathery. Lower surface: Leathery with fine hairs.		Texture.—Upper surface: Smooth with fine hairs.
Petioles.—Absent.	20	Lower surface: Smooth.
Venation pattern.—Pinnate.		Color.—Upper surface: RHS 143A. Lower surface: RHS 138A.
Venation color.—Upper surface: RHS N137A. Lower surface: RHS 138A.		Reproductive organs:
Flower buds:	25	Androecium.—Location: On disc and ray florets. Stamens: Shape: Filamentous. Quantity: Numerous, 70 to 100. Filament length: 0.5 cm. Filament diameter: less than 0.1 cm. Anther: Shape: Lanceolate. Color: RHS 77A. Length: 0.3 cm. Diameter: Less than 0.1 cm. Pollen: Color: RHS 17A. Amount: Sparse.
Shape.—Round-ovoid.		Gynoecium.—Location: On the phyllary. Pistils: Number: Numerous, 50 to 70. Length: 0.6 cm. Diameter: Less than 0.1 cm. Stigma: Color: RHS 79A. Shape: Tapering filamentous and split in two parts. Length: Less than 0.1 cm. Diameter: Less than 0.1 cm. Style: Color: RHS NN155A. Length: 0.3 cm. Diameter: Less than 0.1 cm.
Length.—1.1 cm.		Fruit and seed set: None observed to date.
Diameter.—0.9 cm.		Disease and pest/insect resistance: No disease and pest/insect resistance observed.
Color (at tight bud just before the ray florets unfold).—RHS 138A.	30	COMPARISON WITH PARENTAL LINES AND KNOWN VARIETY
Inflorescence:		‘KLEOE18301’ is a distinct variety of <i>Osteospermum</i> and is distinguished from its parents as described in Table 1.
Type.—Composite, single.		
Blooming habit.—Upright, with flower stems.		
Quantity of inflorescences per plant.—23.		
Lastingness of the inflorescences on the plant.—10 to 15 days.	35	
Fragrance.—Present.		
Inflorescence diameter.—6.5 cm.		
Inflorescence depth.—0.9 cm.		
Disc diameter.—1.2 cm.	40	
Disc floret:		
Quantity per inflorescence.—36.		TABLE 1
Shape.—Tubular.		
Tube color.—Closed: RHS NN155A. Mature: RHS N115B.	45	Characteristic 'KLEOE18301' Female Parent Male Parent
Length.—0.6 cm.		Disc Color Blue 'OE-2010-0382' 'Sunny'
Diameter (at apex).—0.2 cm.		Earliness Medium late Late Early
Apex.—Acute.		
Apex color.—RHS 79A.	50	‘KLEOE18301’ is most similar to the commercial <i>Osteospermum</i> variety ‘Flower Power Light Pink’. Differences between the varieties are described in Table 2.
Base.—Acute.		
Base color.—RHS 145D.		
Margin.—Entire.		
Ray floret:	55	TABLE 2
Quantity per inflorescence.—16.		Comparison with Similar Variety
Shape.—Oblanceolate.		
Color.—Upper surface: RHS NN155C (apical), RHS NN155C (Middle), and RHS N82B (basal). Lower surface: Main color RHS N155A with stripes colored RHS 97A.	60	Characteristic 'KLEOE18301' 'Flower Power Light Pink'
Length.—3.6 cm.		Flower color White Light Pink
Width.—1.1 cm.		Growth Medium Compact
Apex.—Obtuse.		Earliness Medium early Early
Base.—Acute.		
Margin.—Entire.	65	We claim:
Texture (both surfaces).—Smooth.		1. A new and distinct variety of <i>Osteospermum</i> plant designated ‘KLEOE18301’ as illustrated and described herein.
